VENETIAN BLIND

Siegfried F. Mayer, Lock Haven, Pa., assignor to
May-Sloan, Inc., Lock Haven, Pa., a corporation
of Pennsylvania

Application August 1, 1950, Serial No. 177,112

4 Claims. (Cl. 160—178)

1

This invention relates to Venetian blinds, and more particularly to an improved base bar or bottom slat for Venetian blinds, and aims generally to improve existing structures of this type.

A primary object of the invention is the provision of a base bar for Venetian blinds which is simple and economical in construction and which is formed of relatively heavy material, such as metal, for stabilizing the blind and maintaining the tapes thereof under tension when the blind is in a "down" position and which also assists in the raising and lowering steps.

Another object of the invention is the elimination of the usual wooden stabilizing and similar type base bar or slat and the substitution thereof for a hollow tubular steel or like metallic bar made up of complementary interfitting half sections releasably held together.

A further object of the invention is the provision of a base bar for Venetian blinds providing an improved construction for the releasable attachment of runner tapes and elevating cords thereto.

A still further object of the invention is the provision of a base bar for Venetian blinds and the like made up of complementary sections which may be readily assembled in gripping relation with the runner tapes and disassembled, as desired, for shortening or lengthening the blind without the use of special tools or other equipment.

Another object of the invention is the provision of a Venetian blind construction having an improved form of means for holding the tapes in position.

In the drawings—

Fig. 1 is a perspective view of a portion of a Venetian blind embodying the invention;

Fig. 2 is an exploded perspective view of the base bar;

Fig. 3 is a vertical cross-sectional view of the base bar taken on the line 3—3 of Fig. 1 and showing the manner of clamping the tapes;

Fig. 4 is a vertical cross-sectional view of the base bar taken on the line 4—4 of Fig. 1;

Fig. 5 is a longitudinal cross-sectional view of the base bar partially assembled;

Fig. 6 is a plan view of a portion of a modified form of base bar;

Fig. 7 is an end view of the base bar shown in Fig. 6; and

Fig. 8 is a vertical cross-sectional view taken on the line 8—8 of Fig. 6.

Referring to the drawings, the invention is illustrated as embodied in a Venetian blind 10 hav-

2

ing a base bar 11 suspended from a header (not shown) by means of elevating cords 12. Fabric runner tapes 13 suspended from the header are disposed on opposite sides of the base bar 11, and connected thereto in a novel manner as will be more apparent hereinafter.

The tapes 13 are disposed on opposite sides of the elevating cords 12 and are preferably of the ladder type, being interconnected by means of a plurality of vertically spaced slat-supporting cross-tapes or webs 14 of textile material, secured by stitching or the like to the inner faces of the tapes 13. The cross tapes 14 are of less width than the tapes 13, and at least some of them are secured to the tapes 13 adjacent the outer edges thereof, so as to be disposed outwardly of the elevating cords 12. This insures proper alignment of the tapes and slats relative to the elevating cords 12.

20 The slats 15 of the blind are preferably formed of the usual metal Venetian blind slats, being of a length approximately equal to the base bar 11, and either of flat or slightly convexed cross-section, as desired. Such metal slats are conveniently formed of sheet metal of approximately 0.01 inch in thickness and are highly flexible both longitudinally and transversely.

25 The slots 15 rest loosely on the cross-tapes 14 and at the ends thereof are provided with T-shaped slots 16 for receiving the elevating cords 12. This provides for easy mounting and dismounting of the slats for ready replacement, cleaning or repair.

The base bar 11 comprises a pair of opposed 30 complementary sections secured together to form a hollow relatively flat tubular member. It is preferably formed of sheet metal of a thickness to give the desired strength and having sufficient weight to insure that the Venetian blind hangs evenly.

In the preferred embodiment of the invention shown in Figs. 1 to 5, the complementary sections 17 and 18 are bent transversely of the length thereof to form oppositely disposed convexly 45 curved portions 19 and 20 having inwardly extending flanges 21, 22, 23 and 24 at the side edges thereof adapted for interfitting engagement. The radius of curvature of the sections is desirably relatively large so that when assembled with the flanges 21—24 in interfitting engagement a relatively flat oval-shaped hollow tubular member will be formed. Such curvature may be the same for both sections or alternatively, as illustrated, the radius of curvature of the upper section 17 may be somewhat greater than that of the

lower section 18 so that the surface thereof is correspondingly somewhat flatter.

The sections 17 and 18 are held together in assembled relation by end caps 27 and 28 having base portions 29 and 30 provided with flanges 31 and 32 extending outwardly substantially at right angles from the peripheral edges thereof. The flanges 31 and 32 are shaped to fit over and closely embrace the ends of the tubular base bar 11 and are preferably of a size slightly larger than the cross-sectional area of such ends so that they may readily be forced thereover when the tapes are clamped between the complementary sections as hereinafter described.

The end caps 27 and 28 are resiliently held in position on the ends of the base bar 11 by bowing or otherwise permanently bending one or both of the complementary sections 17 and 18, so that when fitted together the ends thereof tend to move apart by virtue of such permanent set or bend and the resiliency of the metal. In the illustrated embodiment of Figs. 1-5 both of the sections 17 and 18 have a permanent set inwardly intermediate the ends thereof so that when fitted together with the intermediate portions in engagement the ends are normally spaced apart in the absence of some restraining means. The end caps may readily be mounted over the normally spaced-apart ends of the sections when they are forced together. When released, the ends of the sections will tensionally engage the flanges of the end caps thereby holding them securely in position.

In accordance with the invention, the tapes 13 and 14 are secured to the base bar 11 by clamping the end portions thereof between the ends of the sections 17 and 18. As hereinabove indicated, the end caps are designed to accommodate the slight increase in size of the ends of the sections occasioned by the thickness of the tapes clamped therebetween, but have a sufficiently snug fit therewith to insure that the tapes are securely and tightly clamped.

The elevating cords are secured to the base bar 11 by passing them through openings 33 and 34 in the top section 17 thereof and then knotting the ends thereof as shown at 35 prior to assembly of the parts. Such knots are disposed between the sections 17 and 18 and hence are not visible when the base bar is assembled.

In assembling the base bar 11 with the blind 10 the elevating cords are first secured to the upper section 17 in the manner above described. The sections 17 and 18 are then fitted together with the ends of the tapes properly positioned between the flanges 21-24 thereof, the ends of the sections then forced together in any suitable manner and the caps placed thereon. The caps hold the sections together with the tapes securely clamped therebetween and the caps in turn are securely held in mounted position by virtue of the inwardly bowed or bent construction of the sections and the resiliency of the metal which cause the ends of the sections to tensionally engage the flanges of the caps.

The base bar 11 may readily be disassembled merely by removing the end caps. This permits ready access to the ends of the elevating cords and tapes so that they may easily be shortened, lengthened or otherwise changed as desired.

In Figs. 6-8 I have shown a modified form of base bar 36 comprising a pair of opposed elongated plates 37 and 38 angularly bent inwardly toward each other intermediate the side edges thereof and assembled together to form a hollow

tubular member which is substantially trapezoidal in cross-sectional shape. The plates 37 and 38 are preferably bent adjacent opposite side edges thereof to an angle somewhat less than 90 degrees to form opposed longer leg portions 39 and 40 and opposed shorter leg portions 41 and 42. Variations in the extent and line of bend may, however, be varied.

In this form of the invention the opposed sections 37 and 38 are releasably held together with the edges of the shorter leg portions 41 and 42 disposed against the adjacent faces of the longer leg portions 39 and 40 inwardly of the side edges thereof. Bolts 43 and nuts 44 or similar attaching means may be used to secure the sections together.

The ends of the tapes are clamped between the edges of the shorter leg portions and the adjacent faces of the longer leg portions and are securely held therebetween by the attaching bolts 43 and nuts 44. The elevating cords are secured to the upper sections 37 by passing them through openings 45 therein and then knotting them as shown at 46.

This embodiment of the invention is likewise formed of sheet metal and is sufficiently heavy to insure that the blind hangs evenly. Ready assembly and disassembly of the plates 37 and 38 is possible merely by removing the attaching means 43 and 44 thereby permitting access to the ends of the tapes and elevating cords to lengthen or shorten the blind.

It will thus be seen that the present invention provides an improved construction of Venetian blind wherein the base bar is formed of complementary sections releasably held together and designed to clamp the ends of the tapes therebetween. Such bars may be quickly and easily assembled and disassembled, thus permitting access to the tapes and elevating cords to lengthen or shorten them. When formed of a relatively heavy material such as sheet metal, the bars have sufficient weight to cause them to hang evenly and straight.

Although I have illustrated and described a preferred form of the invention, I do not intend to be limited thereby as the scope of the invention is best defined in the appended claims.

This application is a continuation-in-part of my co-pending application Serial No. 8,205, now U. S. Patent 2,523,038.

I claim:

1. A base bar for Venetian blinds comprising a pair of transversely rounded complementary sections adapted for interfitting engagement to form a tubular member, one of said sections being formed of a resilient material and in its free condition being bowed along its length, and removable cap means adapted to engage the ends of the sections to bow the one section in an opposite direction to tensionally hold said sections in assembled relation.

2. In a Venetian blind a base bar comprising a pair of transversely bent elongated plate members adapted to be assembled in interfitting engagement to form a tubular member, a plurality of tapes clamped between said plates adjacent the ends thereof, one of said members being resilient and normally bowed inwardly along its length, and restraining means acting on the ends of the plate members for holding said members together in clamping relation to said tapes.

3. In a Venetian blind a tubular-like slat member comprising a pair of complementary transversely curved sections, at least one of said sec-

tions being normally bowed inwardly along the length thereof, a plurality of tapes on opposite sides of said slat member and having the ends thereof positioned between said sections, cap members fitted over the ends of said tubular member for holding the sections in clamping engagement with said tapes and longitudinally bending said one section whereby the ends of the sections are tensionally clamped against the restraining action of said cap members.

4. A Venetian blind comprising a hollow tubular base bar formed of a pair of interfitting complementary resilient sections, a plurality of tapes positioned between said plate members intermediate the ends thereof, each of said sections being bowed along its length inwardly intermediate the ends thereof whereby said ends are in

spaced apart relation when interfitting in unrestrained assembly, and means securing the ends of said sections together in clamping engagement with said tapes in opposition to the tendency thereof to separate.

SIEGFRIED F. MAYER.
